UNITED STATES PATENT OFFICE.

HOMER ECKERSON, OF MECHANICSVILLE, NEW YORK.

DESIGN FOR A CHAIR.

44,752.

Specification for Design.

Patented Oct. 21, 1913.

Application filed August 13, 1913. Serial No. 784,615. Term of patent 7 years.

To all whom it may concern:

Be it known that I, HOMER ECKERSON, a citizen of the United States, residing at Mechanicville, in the county of Saratoga and State of New York, have invented a new, original, and ornamental Design for Chairs, of which the following is a specification, reference being had to the accompanying drawing, forming part thereof.

The single figure of the drawing is a view

in perspective of a chair, showing my new design.

I claim:

The ornamental design for a chair as shown.

HOMER ECKERSON.

Witnesses:

W.M. L. HOWLAND,
NEWTON T. BRYAN.
